(57) **CLAIM**

The ornamental design for an automotive mounting bracket, as shown and described.

DESCRIPTION

FIG. 1 is a perspective view, taken from the front, left side, and top, of an automotive mounting bracket, in accordance with our new design;

FIG. 2 is a perspective view, taken from the rear, right side, and bottom, of the automotive mounting bracket shown in FIG. 1;

FIG. 3 is a top plan view of the automotive mounting bracket shown in FIG. 1;

FIG. 4 is a front elevation view of the automotive mounting bracket shown in FIG. 1;

FIG. 5 is a bottom plan view of the automotive mounting bracket shown in FIG. 1;

FIG. 6 is a rear elevation view of the automotive mounting bracket shown in FIG. 1;

FIG. 7 is a side elevation view of the automotive mounting bracket shown in FIG. 1, taken from the left side of FIG. 4; and,

FIG. 8 is a side elevation view of the automotive mounting bracket shown in FIG. 1, taken from the right side of FIG. 4.

The broken lines in the drawings illustrate portions of the automotive mounting bracket and form no part of the claimed design.

1 Claim, 2 Drawing Sheets
